UNITED STATES PATENT OFFICE.

FREDERICK GLASS, OF KINGSTON, NEW YORK, ASSIGNOR OF ONE-HALF TO LAWRENCE F. BANNON, OF KINGSTON, NEW YORK.

VALVE.

No. 927,348.

Specification of Letters Patent.

Patented July 6, 1909.

Application filed March 21, 1906. Serial No. 307,260.

To all whom it may concern:

Be it known that I, FREDERICK GLASS, a citizen of the United States, residing at Kingston, in the county of Ulster and State of New York, have invented new and useful Improvements in Valves, of which the following is a specification.

This invention relates to valves such as are particularly intended for use in connection with steam for hot water radiators, although the valve of the present invention may be adapted for use in other connections.

In placing radiators difficulty is often experienced in properly connecting them with their steam or hot water supply pipes. This is due to the fact that the valves or connecting devices usually employed, require that the radiator be placed a certain exact distance away from the supply pipe. If the radiator be too near or too far it is necessary to work the same into position before it can be connected properly with the supply pipe, and as the radiators are usually heavy, two or more men are required for placing them in position.

The object of the present invention is to improve the construction of radiator valves in such manner as to render them adjustable, so that if the radiator has been placed a trifle too near or a trifle too far from the supply pipe, the proper connections can be made without the necessity of moving the heavy radiator.

With the foregoing and other objects in view, which will appear as the description proceeds, the invention resides in the combination and arrangement of parts and in the details of construction hereinafter described and claimed as a practical embodiment thereof.

In the accompanying drawing forming part of this specification; Figure 1 is a side elevation of a valve constructed in accordance with the present invention, a portion of the radiator being shown in section. Fig. 2 is a vertical section, partly in elevation, taken through the construction shown in Fig. 1. Fig. 3 is a detail view of the packing ring.

Like reference numerals indicate corresponding parts in the different figures of the drawing.

The reference numeral 1 indicates an ordinary valve casing which is screwed or otherwise suitably secured to a supply pipe 2. Located in the casing 1 is a rotatable

sleeve 3 having an opening 4 to control the passage of fluid through the valve. When the sleeve 3 is turned so that the opening 4 registers with the end of a lateral branch or tubular extension 5 formed on the valve casing 1, the valve is open, and when said sleeve 3 is turned so that the opening 4 is out of register with the tubular extension 5, the valve is closed, as will be readily understood. The sleeve 3 is operated by means of a stem 6 which extends through the head 7 of the valve casing and is provided with a handle 8. Any suitable packing 10 held in position by a screw cap 11 is employed for rendering the valve steam tight.

The parts thus far described are old and well known in the art, for which reason they are not specifically claimed herein.

In carrying out the present invention a tube 12 is adjustably and rotatably fitted into the tubular extension 5 of the valve. The tube 12 is threaded at the end 13 thereof so that it can be screwed into the radiator, a portion of which is indicated at 14. The tube 12 is also formed with an octagonal or other suitable collar 15 adapted to receive a wrench for use in screwing the tube 12 into the radiator. If desired, the tube 12 can be screwed into the radiator to such an extent as to seat the flange 15 against the outer surface of the radiator so as to prevent leakage through the joint.

Loosely surrounding the tube 12 is a collar 17 which preferably is triangular in cross section. The collar 17 is intended to be forced up against the internally coned end 18 of the extension 5 by means of a collar 19 which is contracted at the end 20 so as to fit closely around the tube 12, and is enlarged at the end 21 so as to fit around the end of the extension 5 and to be suitably secured thereto by means of screw threads or the like. A packing ring 22 is suitably interposed between the end 20 of the collar 19 and the triangular collar 17 as shown in Fig. 2.

In using the improved device it is preferred that the radiator be placed a convenient distance away from the supply pipe 2 in the usual manner. The tube 12 which is usually telescoped within the tubular extension 5, is then drawn down sufficiently to permit it to be screwed into the radiator. The collar 19 is then screwed on to the extension 5 and tightened so as to force the triangular collar 17 against the internally coned end 18 of the extension 5, whereby said col-

lar 17 is tightly jammed or pressed around the tube 12, thus forming a perfectly tight joint between the tube 12 and extension 5.

Having thus described the invention what is claimed as new is:

A cylindrical valve having open threaded ends and a smooth internal surface and also having a laterally-projecting cylindrical extension of uniform bore throughout its length 10 and provided with a smooth internal surface, said extension having its outer end undercut to form an internal bevel, an external thread on the outer end of the extension adjacent the bevel thereof, a cylindrical tube having a 15 portion of uniform external diameter snugly fitting in the said extension for sliding contact therewith and capable of longitudinal adjustment throughout the length of the extension, an external thread on the end of the 20 tube opposite from that disposed in the extension, the threaded end of said tube being adapted to be screwed into a fixed structure, a non-circular flange on the tube forming an annular shoulder at the inner end of the extension thread of the tube, a removable hol- 25

low cylindrical valve rotatably mounted in the casing and snugly fitting therein and having a port in its side adapted to communicate with the extension, said tube being capable of entering the casing when the valve is removed and the non-circular flange serving to limit the screwing of the tube into the said structure, a packing ring bearing against the bevel of the extension, a nut threaded on the extension and engaging the packing ring 30 to compress the same into contact with the tube and frictionally holding the valve casing and tube together, a pipe threaded in the valve casing at one end, a cap threaded on the casing at the opposite end and coöperating with the said pipe for preventing longitudinal movement of the valve, and a valve stem secured to the valve and extending through the said cap.

In testimony whereof, I have affixed my 45 signature in presence of two witnesses.

FREDERICK GLASS.
